UNITED STATES PATENT OFFICE

2,472,144

ELECTRIC HEATER FOR SOFTENING
THERMOPLASTICS

John V. Calhoun, Haverford, Pa., assignor to
Edwin L. Wiegand Company, Pittsburgh, Pa., a
corporation of Pennsylvania

Application July 8, 1947, Serial No. 759,557

2 Claims. (Cl. 219—19)

1

My invention relates to electric heating, and a principal object of my invention is the provision of an electric heater satisfactory for melting or softening viscous or other material in a container, thus to facilitate removal of the material from the container.

In this application I have shown and described, for purpose of illustration, one embodiment which my invention may assume, and in the drawings accompanying this specification and forming part of this application:

Figure 1 is a view of an electric heater according to my invention, partially in front elevation and partially in vertical section;

Figure 2 is a top plan view of the heater of Figure 1;

Figures 3, 4, and 5, are transverse sections on the lines 3—3, 4—4, and 5—5, of Figure 1; and

Figure 6 is a circuit diagram showing one manner in which the heater may be connected.

The electric heater herein shown and described comprises two sheathed embedded-resistor electric heating elements 11, herein shown as triangular in cross-section, having their active sections 12 disposed in recesses in the lower face of a base 13, having their terminal portions 14 rising through openings 15 provided in the base 13, and held in position by means of a face plate 16 overlying the lower face of the base 13 and herein shown as secured to the base 13 by means of a series of bolts 17 extending through aligned apertures in the face plate 16 and base 13.

Rising from the base 13 is a frame herein shown as comprising two tubes 18 screw-threaded in the openings 15 in the base 13, T's 19 screw-threaded to the upper ends of the tubes 18, nipples 20 screw-threaded into the side openings of the T's 19, and a union 21 connecting the two nipples 20 and completing a cross-brace between the two sides of the frame, while welded or otherwise suitably secured to the upper ends of the T's 19 is a sheet metal housing 22 containing a thermostatic switch 23 adjustable by means of a knob 24 positioned above the top of the casing 22.

With this construction the electric heating elements 11 are energized under control of the thermostatic switch 23 by means of conductors 25 extending from the heating element terminals 26 through the tubes 18 and T's 19 into the interior of the casing 22 and connected to the thermostatic switch 23, and conductors 27 extending to the thermostatic switch 23 from a suitable source of electric power, and the thermostatic switch 23 is responsive to operating tem-

2

perature by means of a thermostat bulb 28 carried by a cross-frame 36 clamped to the tubes 18 and operatively connected to the thermostatic switch 23 by means of a connecting tube indicated at 29.

To produce balanced heating of the face plate 16, preferably the two elements 11 are at least approximately equal, and to avoid inductance on alternating current, preferably the conductors 27 are so connected to the thermostatic switch 23 that the two currents within each of the tubes 18 and T's 19 flow in opposite direction, for example, as indicated by the diagram, Figure 6.

In operation, the heater is placed in position with the face plate 16 resting on the viscous or other material to be heated or softened; the thermostatic switch is set for the desired temperature, and thereupon the heater will progressively melt or soften the viscous or other material, whereby the material may be removed from the container, but avoiding any temperature that would injure the material, and particularly important in this respect is the location of the thermostat bulb 28 substantially above the base 13, whereby the operation of the device is responsive directly to the temperature of the softened or melted material.

After operation any material that may have entered the tubes 18 may flow out through openings 20, while for convenience in handling preferably the heater is provided with handle means herein shown as comprising a plate 31 embracing the tubes 18 immediately below the T's 19, a lower channel 32 extending transversely below the plate 31, an upper channel 33 extending transversely above the top of the housing 22, connecting bolts 34 extending between the lower channel 32 and the upper channel 33, and an eye-bolt 35 secured to the upper channel 33.

As will be understood, the heater is made relatively heavy, whereby the apparatus will come into close contact with the viscous or other material and further will descend into the material as rapidly as the melting or softening is accomplished, and to facilitate the latter function preferably the base 13 and face plate 16 are provided with a plurality of apertures 37, as shown.

From the foregoing it will be apparent that the embodiment of my invention herein shown and described accomplishes the object specifically stated. Further it will be apparent that the said embodiment also accomplishes various other desirable objects and embodies various desirable advantages. On the other hand, obviously various changes and modifications may be made, and

various other embodiments may be substituted, within the spirit of my invention, and retaining some or all of the advantages and accomplishments of the present embodiment, and accordingly it will be understood that the present disclosure is illustrative only, and that my invention is not limited thereto.

Whereupon I claim:

1. An electric heater particularly for melting or softening a body of material within a container to facilitate removal of the material from the container, comprising a platen adapted to be imposed on the body of material, metal-sheathed electric heating means carried by said platen constructed and arranged to heat said platen to cause said platen to impart heat to said material to melt or soften said material, structural means comprising a superstructure disposed a substantial distance above said platen and duct means rising from said platen and connecting said platen and said superstructure, electric conductors for supplying electric energy to said heating means, connected to said heating means and extending through said duct means, and thermostatic switch means responsive to the temperature of said platen to control the supply of electric energy to said heating means to avoid increase in temperature of said platen above approximately a set value, comprising switch means connected in circuit with said heating means and mounted on said structural means at a substantial distance above said platen to avoid immersion of said switch means in the material upon sinking of said heater upon melting or softening of the material.

2. An electric heater comprising a platen adapted to be imposed on a body of material, a

pair of electric heating elements carried by said platen constructed and arranged to heat said platen to cause said platen to impart heat to said material to melt or soften said material, a superstructure disposed above said platen and comprising a pair of ducts rising from said platen and to which said platen is connected, electric conductors for supplying electric energy to said heating elements extending through said ducts 10 with the two conductors for each of said heating elements extending one through one of said ducts and the other through the other of said ducts and the two conductors in each of said ducts connected one to one side of the supply and the other to the other side thereby to reduce or avoid induction of current in said ducts when the heater is operated on alternating current, and thermostatic switch means responsive to the temperature of said platen to control the supply of electric energy to said heating means to avoid increase in temperature of said platen above approximately a set value.

JOHN V. CALHOUN.
